PORTABLE DAM

Alonzo Blevins, Jr., Huntington, W. Va.

Application February 9, 1951, Serial No. 210,169

3 Claims. (Cl. 220—86)

1

This invention relates to portable dams and more particularly to a dam for keeping water out of ground openings, such as the filler openings for gasoline storage tanks.

In operating gasoline service stations it has been found necessary to locate the filler openings for the underground storage tanks in the pavement adjacent the service pumps in order to render the openings readily accessible to the tank trucks which supply the gasoline or other fuel to the storage tanks. It has also been found necessary to locate the closure caps for these openings substantially flush with the pavement so they will not interfere with vehicles or pedestrians moving over the pavement. When a closure cap is removed for any purpose, such as supplying additional gasoline to the tank or inserting a measuring stick, the top of the opening is flush with the surface of the pavement and surface water, such as that from heavy rain or melting snow, will run into the opening and into the storage tank for which the filler opening is provided.

While means are provided for periodically pumping water from the storage tanks, an excessive amount of water entering the tanks not only necessitates frequent pumping but may rise in a tank to the intake of the service pump so that water may be pumped into the fuel tanks of automotive vehicles.

There are also ground openings for other purposes in pavements which openings should be protected from inflow of surface water when opened.

It is, therefore, among the objects of the present invention to provide a portable dam which can be placed around such a ground opening and sealed to the pavement to preclude the flow of surface water into the opening when the latter is open or uncovered; which dam comprises a unitary structure which is easy to carry and to place in operative position around a ground opening and will remain in position and in sealing engagement with the pavement by its own weight and without the use of fasteners of any kind; which carries a body of plastic sealing material for contact with the pavement around the ground opening to provide a watertight seal; which includes an outer body of resilient material to prevent breakage and facilitate making and maintaining a seal with the pavement; and which is simple and durable in construction, economical to manufacture, and positive and effective in use.

Other objects and advantages will become apparent from a consideration of the following description and the appended claims in conjunction with the accompanying drawing wherein:

Figure 1 is a diagrammatic cross sectional view fragmentarily illustrating a storage tank, filler opening and covering pavement with a portable dam, illustrative of the invention, disposed on the pavement surrounding the filler opening;

2

Figure 2 is a top plan view on an enlarged scale of the portable dam and a fragmentary portion of the dam supporting pavement; and

Figure 3 is a cross sectional view on the line 3—3 of Figure 2.

With continued reference to the drawing, the underground storage tank 10 is illustrated as disposed below a pavement 11 having a flat top surface, and a filler pipe 12 extends substantially through the pavement and has its lower end secured to the tank 10 surrounding an aperture 13 in the latter. An annular recess or counterbore is provided in the pavement at the upper end of the filler pipe 12, this recess being lined by an annular collar 14 and the filler pipe 12 is provided with screw threads 15 at its upper end to receive a closure cap, not illustrated.

When the closure cap is threaded onto the upper end of the pipe 12 it closes the pipe and has its upper surface disposed substantially flush with the surface of the pavement 11. When the cap is removed the filler opening through the pavement has its upper end, corresponding to the upper end of the collar 14, flush with the pavement and in position to receive surface water flowing across the pavement from rain, melting snow or other source.

In order to stop this flow of surface water into the filler opening the portable dam, as generally indicated at 16, may be placed on the pavement surrounding the filler opening.

In the arrangement illustrated, the portable dam comprises a circular body of resilient material, such as vulcanized rubber, having an inside diameter somewhat greater than the diameter of the filler opening and a height sufficient to deflect the surface water away from the filler opening but such that if a vehicle were accidentally driven over the filler opening a vehicle wheel would pass over the dam without damage to the vehicle or to the dam.

The annular body of resilient material has a substantially rectangular cross sectional area except that its peripheral surface is concavely curved in a transverse direction so that the body is somewhat thicker at one end than at the other. The body has flat and substantially parallel end surfaces and has an inner annular surface of cylindrical shape and substantially perpendicular to the end surface. Two annular grooves 17 and 18 are provided in and are concentric with the body with the groove 17 opening to the end surface at the narrower end of the body and the groove 18 opening to the end surface at the thicker end of the body. These grooves, as illustrated, are equal in diameter (see Figure 3), are of square or rectangular cross sectional shape and are separated by an annular intermediate body portion 19. A cylindrical wall 20 of substantially uniform thickness covers the inner sides of the grooves and an outer annular wall 21 which tapers

in thickness from one end of the body to the other covers the outer sides of the grooves.

The groove 17 opens to the thinner and upper end of the annular body and an annular body 22 of heavy material, such as lead, is disposed in the groove 17 to increase the weight of the dam. An annular body 23 of plastic sealing material, such as water pump grease, is disposed in the groove 18 so that its exposed surface will contact the surface of the pavement when the portable dam is placed in position on the pavement surrounding a filler opening therein. By manually pressing the dam down around the filler opening the material of the body 23 can be forced against the pavement with sufficient pressure to provide a watertight seal between this body and the pavement and, because of the plastic nature of the material, the material will adhere to the pavement and assist in holding the dam in operative position around the filler opening. In this connection, the fact that the grooves are equal in diameter and concentric with the axis of the annular body in which they are formed will cause the groove 17 to be disposed immediately above and in vertical alignment with the groove 18, as a result of which the downward pressure exerted by the weight of the lead is transmitted downwardly through the resilient body portion 19, directly against the body of plastic sealing material, thus to force the plastic body into sealing engagement with a supporting surface on which the device is horizontally positioned.

While the portable dam has been illustrated in circular form, it may obviously be made in other shapes, such as rectangular, hexagonal or even U shaped, without in any way exceeding the scope of the invention, and may be made in various sizes for different types of ground openings.

After the portable dam has been placed around the filler opening and sealed to the surrounding pavement in the manner indicated above, the cover cap for the filler opening may be removed and there will be no danger of surface water flowing into the filler opening. An object, such as the hose nozzle 24, may then be inserted through the dam and into the upper end of the filler pipe 12 to flow liquid, such as gasoline or other motor fuel, into the underground storage tank.

The portable dams may be manufactured and sold without the plastic sealing material and this material may be filled into the groove 18 when it is desired to use the dam and may be replenished whenever necessary since grease of suitable characteristics is carried by nearly all filling stations. The dam may be carried on the fuel transporting tank truck or may be kept at the filling station, as may be desired, since it is of light weight and occupies very little space and can be stored or transported without deterioration.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. A portable dam comprising an annular body of resilient material of substantially rectangular cross sectional shape and having therein spaced apart annular grooves opening to respectively op-

posite end faces of said body, said grooves being equal in diameter and being concentric with said body for disposition of the grooves in substantially vertical alignment when the body is positioned upon a substantially horizontal supporting surface, an annular body of heavy material in one of said grooves, and an annular body of plastic sealing material in the other of said grooves, said body of heavy material constituting means effective to transmit pressure to the plastic body along lines paralleling the axis of the first named body to form a seal between said first named body and a surface supporting the same.

2. A portable dam comprising a body of elastic material having an opening therethrough and having substantially parallel end faces extending around said opening, said body also having grooves therein opening one to each of said end faces and extending around said opening, said grooves being equal in diameter and being concentric with said body for disposition of the grooves in substantially vertical alignment when the body is positioned upon a substantially horizontal supporting surface, a body of heavy material in one of said grooves to increase the weight of said dam, and a body of plastic sealing material in the other of said grooves, said body of heavy material constituting means effective to transmit pressure to the plastic body along lines paralleling the axis of the first named body to form a seal between said first named body and a surface supporting the same.

3. A portable dam comprising an annular body of vulcanized rubber having an inner annular surface, a peripheral surface and substantially parallel flat end faces, said body also having annular grooves surrounding the opening therein and opening one to each of said end faces, said grooves being separated by an intermediate portion of said body, said grooves being equal in diameter and being concentric with said body for disposition of the grooves in substantially vertical alignment when the body is positioned upon a substantially horizontal supporting surface, an annular body of lead in one of said grooves, and an annular body of plastic sealing material in the other of said grooves, said body of lead constituting means effective to transmit pressure to the plastic body through said intermediate portion along lines paralleling the axis of the first named body, to form a seal between said first named body and the surface supporting the same.
